COMBINED RECORD PLAYER AND AMPLIFIER

Yoshiaki Iida, Katano, Japan, assignor to Matsushita
Electric Industrial Co., Ltd., Osaka, Japan

Filed Mar. 20, 1973, Ser. No. 343,055

Claims priority, application Japan Sept. 20, 1972

Term of patent 14 years

Int. Cl. D14—01

U.S. Cl. D56—4 R

FIG. 1

FIG. 2

FIG. 1 is a right side, top and front perspective view of a combined record player and amplifier, showing my new design; and

FIG. 2 is a left side, top and front perspective view, with a transparent dust cover positioned thereon.

The rear of the combined record player and amplifier is plain and unornamented.

Portions of the figures are shaded to indicate contrast and appearance, and portions are diagonally lined to indicate transparency.

The structure which would be visible through the transparent cover of FIG. 2 has been omitted for convenience in illustration.

I claim:

The ornamental design for a combined record player and amplifier, as shown and described.
